UNITED STATES PATENT OFFICE.

JOHN C. BISHOP, OF ORNVILLE, MAINE.

SHINGLE-PRESS.

1,218,248.

Specification of Letters Patent. Patented Nov. 27, 1917.

Application filed March 22, 1917. Serial No. 156,705.

To all whom it may concern:

Be it known that I, JOHN C. BISHOP, a citizen of the United States, residing at Ornville, in the county of Piscataquis and State of Maine, have invented certain new and useful Improvements in Shingle-Presses; and I do hereby declare the following to be a full, clear, and exact description of the invention, such as will enable others skilled in the art to which it appertains to make and use the same.

This invention relates to a press for bunching shingles and the primary object of the invention is to provide a press which will compress the thin ends of shingles, for holding the shingles in bunch formation while they are tied, by means of a pair of wooden binders and metal strips which are secured to the binders and extend across the edges of a bundle of shingles.

Another object of this invention is to provide a shingle press as specified which includes a supporting frame shaped so that when the shingles are mounted therein, they will be placed in bunch formation. Said supporting frame has a pair of arms pivotally carried thereby upon the upper surfaces of the free ends of which the lower tie rests while the bunch of shingles is built up above the upper surface thereof; to provide a pair of cams which engage the under surfaces of the pivoted arms so that upon the rotation of the cams the arms will be forced upwardly for tightly pressing together the engaging ends of the shingles of which the bunch is formed, for pressing them against an upper tie which is held in place by a pair of hingedly connected links so that the two ties may be connected by metal strips for holding the shingles in bunch formation.

A further object of this invention is to provide a press as specified which includes a pair of centrally disposed side standards for regulating the width of the bunch of shingles which standards are positioned intermediate the ends of the supporting frame during the building up of a bunch of shingles, and further to provide means for shifting these side standards away from the center of the bunch to permit the bunch to be tied at the center.

With the foregoing and other objects in view, this invention consists in such novel features of construction, combination and

arrangement of parts as will be hereinafter more fully described, illustrated in the accompanying drawings and claimed.

In describing the invention in detail reference will be had to the accompanying drawings wherein like characters designate like and corresponding parts throughout the several views, and in which:

Figure 1 is a top plan view of the improved shingle press.

Fig. 2 is a side elevation of the shingle press in position for receiving bunches of shingles.

Fig. 3 is a side elevation of the press showing it in a compressing position.

Fig. 4 is a section on the line 4—4 of Fig. 2,

Fig. 5 is a detail view illustrating tie structure, and

Fig. 6 is a fragmentary sectional view illustrating the manner of hingedly connecting one end of the supporting structure to the base thereof.

Referring more particularly to the drawings, 1 designates the base of the improved shingle press, which is rectangular shaped, and has standards 2 attached to its corners. The standards 2 are spaced, so that the distance between them is equal to the proper length for a bundle of shingles, and the frame 1 is the proper width for a regulation bundle of shingles. One end pair of the standards 2 have a plate 3 hingedly connected thereto as shown at 4. The spring hinges 4 are attached to the end plate 3 and to the end of the base 1 and they tend to hold the end 3 in vertical position against the standards 2 but they permit the end 3 to be moved downwardly upon the removal of a bound bundle of shingles.

The side rails 5 of the base 1 are provided with slots 6 through which the horizontal portion of the intermediate standards 8, extend. The intermediate or central standards 8 have vertical portions which extend upwardly and outwardly of the frame 1 as clearly shown in Figs. 1 and 3 of the drawings. The horizontal portion 7 which connects the lower ends of the standards 8 extends transversely across the frame 1 and is slidably mounted in the slots 6. The connecting bar 7 has rods 9 and 10 connected thereto as shown at 11. The rod 9 is pivotally connected at 12 to a pivotally mounted

- arm 13, which arm is pivotally connected to the frame 1 and to a hand lever 14 as shown at 15. The rod 10 is connected to the hand lever 14 as shown at 16. The hand lever 16 5 is pivotally connected through the medium of ears 17 to the supporting base 1 for movement in a horizontal plane, so that when the hand lever 14 is rocked or oscillated it will move the connecting bar 7 and consequently 10 move the vertical standards 8. When a bundle of shingles is being formed within the press, the standards 8 are positioned at the inner ends of their movement, or namely at the center of the frame 1 and the shingles 15 are built up or piled upon a tie as indicated at 19 in Fig. 4, between the standards 8 so that the thin ends of the shingles will overlap, as is ordinary in the forming of bundles of shingles.
- 20 The lower or bottom tie 19 rests upon the forward upper free ends of pivoted arms 20 and 21. The arms 20 and 21 are pivotally mounted upon a rod 22 which extends transversely across the frame 1 near one end 25 of the frame. The inner free ends of the arms 20 and 21 rest upon the periphery of cams 23 and 24. The cams 23 and 24 are mounted upon a shaft 25 which extends transversely across the frame 1 and is rotatably supported by suitable bearings 26. Hand levers 27 are mounted upon the ends of the shaft 25 outwardly of the frame 1 and they are provided for rocking the cams 23 and 24 so as to force the pivoted arms 20 30 and 21 upwardly for compressing the overlapping ends of the shingles as shown in Fig. 3 of the drawings, after which the bundle of shingles is tied.
- After the required number of shingles 40 have been placed within the press, the lever 14 is operated for moving the standards 8 outwardly from the center of the supporting frame 1 and the top tie indicated by the numeral 19^a in Fig. 5 of the drawings is placed 45 across the overlapping ends of the shingles after which the links 28 and 29 are moved upon their pivots 30 so that their upper ends will extend over the ends of the upper tie 19^a. The levers 27 are then operated 50 which will rock the cams 23 and 24 and force the inner ends of the pivoted arms 20 and 21 upwardly, compactly compressing the overlapping ends of the shingles between the bottom tie 19 and the top tie 19^a. Prior to 55 the placing of the bottom tie 19 upon the free ends of the arms 20 and 21, metal strips 19^b and 19^c are secured to its ends and after the bundles of shingles have been compressed between the top tie 19^a and the bottom tie 19, the metal strips 19^b and 19^c are passed upwardly along the edges of the bundle and attached to the upper surface of the end of the top tie 19^a which securely binds or ties the overlapping ends of the 60 shingles of which the bundle is formed 65

after the bundle has been properly tied, the hinged end 3, is moved outwardly and the bundle of shingles removed.

What is claimed is:

1. In a shingle bundle press, a supporting base, a pair of arms pivotally carried by said base, a pair of side standards adjustably carried by said base, said pivoted arms adapted to support a bottom bundle tie, means for holding a top tie on the top edge 75 of bundle of shingles, and means for forcing said pivoted arms upwardly for compressing the overlapping ends of the shingles forming a bundle.
2. In a shingle bundle press, a supporting 80 base, a pair of arms pivotally carried by said base, a pair of side standards adjustably carried by said base, said pivoted arms adapted to support a bottom bundle tie, means for holding a top tie on the top edge 85 of a bundle of shingles, and means for forcing said pivoted arms upwardly for compressing the overlapping ends of the shingles forming a bundle, and means for adjusting the position of said vertical side standards. 90
3. In a shingle bundle press, a supporting base, a pair of side standards disposed centrally along the sides of said base, a pair of arms pivotally connected to said base and having their free ends positioned between 95 said standards, said free ends adapted to support the lower tie for a bundle of shingles, a pair of substantially U-shaped links pivotally connected to said base and adapted for clamping a top tie upon the 100 top of a bundle of shingles.
4. In a shingle bundle press, a supporting base, a pair of side standards disposed centrally along the sides of said base, a pair of arms pivotally connected to said base 105 and having their free ends positioned between said standards, said free ends adapted to support the lower tie for a bundle of shingles, a pair of substantially U-shaped links pivotally connected to said base rails 110 and adapted for clamping a top tie upon the top of a bundle of shingles, a shaft rotatably carried by said supporting base, cams mounted upon said shaft, said cams engaging the under surfaces of the free ends 115 of said pivoted levers for forcing the pivoted levers upwardly for compressing a bundle of shingles positioned upon the levers.
5. In a shingle bundle press, a supporting 120 base, a pair of side standards disposed centrally along the sides of said base, a pair of arms pivotally connected to said base and having their free ends positioned between said standards, said free ends adapted to support the lower tie for a bundle of shingles, a pair of substantially U-shaped links pivotally connected to said side rails 125 and adapted for clamping a top tie upon the top of a bundle of shingles, a shaft ro- 130

tatably carried by said supporting base, cams mounted upon said shaft, said cams engaging the under surfaces of the free ends of said pivoted levers for forcing the piv-
5 oted levers upwardly for compressing a bundle of shingles positioned upon the levers, a cross bar connecting the lower edge of said centrally disposed side standards, a hand lever connected to said cross bar for

moving said standards away from the cen- 10 ter of the supporting base.

In testimony whereof I affix my signature in presence of two witnesses.

JOHN C. BISHOP.
